SLOPE MEASURING INSTRUMENT

Lloyd K. Rosenvold and Robert J. Rosenvold, both of
Rte. 1, Box 150, Montrose, Colo.

Filed Oct. 21, 1964, Ser. No. 82,263

Term of patent 14 years

(Cl. D52—6)

FIG.1

FIG.2

FIGURE 1 is a top plan view of a slope measuring instrument, showing our new design.

FIGURE 2 is an edge elevational view thereof.

The bottom of the instrument is a mirror image of FIGURE 1.

We claim:

The ornamental design for a slope measuring instrument, as shown and described.
